US00D788081S

(12) **United States Design Patent** (10) **Patent No.:** **US D788,081 S**
Austin-Smith (45) **Date of Patent:** **** May 30, 2017**

(54) **MICROPHONE WITH HOLDER FOR CELL PHONE OR CAMERA**

(71) Applicant: **Worlds Apart Limited**, St Columb Major (GB)

(72) Inventor: **James Austin-Smith**, St Columb Major (GB)

(73) Assignee: **Worlds Apart Limited** (GB)

(**) Term: **15 Years**

(21) Appl. No.: **29/561,172**

(22) Filed: **Apr. 14, 2016**

(30) **Foreign Application Priority Data**

Feb. 19, 2016 (EP) 002993238

(51) **LOC (10) Cl.** **14-01**

(52) **U.S. Cl.**

USPC **D14/226**

(58) **Field of Classification Search**

USPC D14/225, 226, 228, 229; 181/129, 130, 181/135; 379/430, 431; D8/355, 394, D8/396; 381/364, 363, 355, 361, 362, 381/189, 360; 248/411, 454, 453, 448, 248/447, 515, 638, 559, 636, 562, 229, 248/316.7

(57) **CLAIM**

I claim The ornamental design for a microphone with holder for cell phone or camera, as shown and described.

DESCRIPTION

FIG. 1 is a top view of a microphone with holder for cell phone or camera showing my new design;

FIG. 2 is a left side view thereof;

FIG. 3 is a front view thereof;

FIG. 4 is a right side view thereof;

FIG. 5 is a bottom view thereof; and,

FIG. 6 is a back view thereof.

1 Claim, 6 Drawing Sheets
